R. T. DAVIS

BASE FOR A LOUD SPEAKER

Filed Oct. 7, 1926

Fig. 1.

Fig. 2.

Inventor:

*Richard T. Davis,
Boggsenforth, La., Cotton Mills,
Attala Co.,*

UNITED STATES PATENT OFFICE.

RICHARD T. DAVIS, OF CHICAGO, ILLINOIS.

DESIGN FOR A BASE FOR A LOUD SPEAKER.

Application filed October 7, 1926. Serial No. 19,272. Term of patent 3½ years.

To all whom it may concern:

Be it known that I, RICHARD T. DAVIS, a citizen of the United States, residing at Chicago, county of Cook, and State of Illinois, have invented a new, original, and ornamental Design for a Base for a Loud Speaker, of which the following is a specification, reference being had to the accompanying drawings, forming a part hereof, in which—

I claim:

The ornamental design for a base for a loud speaker as shown.

RICHARD T. DAVIS.
